(57) **CLAIM**

The ornamental design for a computing device, as shown and described.

DESCRIPTION

1. Computing device

1.1 : Top isometric view

1.2 : Bottom isometric view

1.3 : Top

1.4 : Bottom

1.5 : Left

1.6 : Right

1.7 : Front

1.8 : Back

Reproduction 1.1 is a top isometric view of a computing device; reproduction 1.2 is a bottom isometric view of the computing device; reproduction 1.3 is a top orthographic view of the computing device; reproduction 1.4 is a bottom orthographic view of the computing device; reproduction 1.5 is a left side orthographic view of the computing device; reproduction 1.6 is a right side orthographic view of the computing device; reproduction 1.7 is a front orthographic view of the computing device; and reproduction 1.8 is a rear orthographic view of the computing device.
